UNITED STATES PATENT OFFICE

154,761

DESIGN FOR A WHEEL BODY

Duncan P. Forbes, Rockford, Ill., assignor to
Gunité Foundries Corporation, Rockford, Ill.,
a corporation of Illinois

Application July 1, 1947, Serial No. 140,050

Term of patent 14 years

(Cl. D14—30)

To all whom it may concern:

Be it known that I, Duncan P. Forbes, a citizen of the United States, residing at Rockford, in the county of Winnebago and State of Illinois, have invented a new, original, and ornamental Design for a Wheel Body, of which the following is a specification, reference being had to the accompanying drawings forming part thereof.

In the drawings:

Figure 1 is an elevational view of the outboard side of a wheel body, showing my new design;

Figure 2 is an elevational view of the edge thereof;

Figure 3 is a side elevational view of the inboard side thereof;

Figure 4 is a perspective view showing the outboard side of the wheel body.

I claim:

The ornamental design for a wheel body, substantially as shown.

DUNCAN P. FORBES.
